SHOE UPPER PRESSING AND SMOOTHING
MACHINEJohn F. Smith, Quincy, Mass., assignor to Milton
L. Dodge, Newburyport, Mass.

Application March 4, 1938, Serial No. 193,947

7 Claims. (Cl. 12—51)

This invention relates to machines for pressing and smoothing the uppers, and particularly the linings of shoes, and more particularly as a final finishing operation. It is particularly concerned with, though not limited to, machines of the well known Dodge type, in which the shoe is supported on a form and the upper is pressed and smoothed against the form by a pair of side presser members which are moved in from opposite sides against the outer face of the shoe upper.

The present invention has for certain of its objects an improved actuating mechanism for the side presser members, and an improved mounting for the individual member facilitating a controlled wiping action of the member on the shoe.

A further object is to provide an improved shoe supporting form adjustable to different sizes of shoes, and, if desired, collapsible automatically when the presser is released to facilitate the placing or removal of shoes with relation thereto and then automatically expandable to a predetermined amount for the pressing operation.

Further objects and advantages will appear from a more complete description of certain embodiments of the invention shown in the accompanying drawings in which

Figure 1 is a fragmentary view, partly in front elevation and partly broken away and in section, of a machine embodying the invention.

Figure 2 is a fragmentary top plan of the machine to a larger scale.

Figure 3 is a front elevation of the parts shown in Figure 2.

Figure 4 is a detail section to a larger scale on line 4—4 of Figure 1.

Figure 5 is a fragmentary side elevation showing the operative mechanism of the machine.

Figures 6 and 7 are detail sections on line 6—6 and 7—7, respectively, of Figure 5, Figure 7 being on a larger scale.

Figure 8 is a detail section on line 8—8 of Figure 3.

Figure 9 is a view partly in elevation and partly in section similar to Figure 8, but showing a modified construction.

As shown best in Figures 1 and 5, the machine comprises an upwardly extending bracket 1 and a downwardly extending bracket 2, the bracket 1 being shown as carried on the upper face of a table or bench such as 3, and the bracket 2 being secured to the front downwardly extending flange 5 of the member 3. A plurality of machines, each provided with brackets such as 1 and 2, may be secured to a single bench or support 3 in con-

venient relation to the operator. The bracket 1 extends out forwardly of the edge of the support 3 in an I section arm 10, and between the rear end of this portion and a pad 11 extending up from the base of the bracket 1, there is pivoted on a pin 12 a pair of arms 15 and 16. One of these arms, such as 16, carries spaced jaws 17, and the other, such as the arm 15, has a single pivot loop 18 positioned between the jaws 17, the pin passing through the jaws 17 and the loop 18.

Secured to or integral with the forward ends of the members 15 and 16 are sections 19 and 20, respectively, of a laterally expandable and contractible shoe-holding form, designated generally at 21, the swinging apart of the arms 15 and 16 causing the form to expand and the swinging of these arms 15 and 16 toward each other causing the form to contract. In contracted condition, a shoe may be readily placed over the form right side up and with its toe projecting forwardly preparatory to the pressing action, after which the form may be expanded to a size suitable for the particular shoe being treated, and there held during the pressing and smoothing operation.

Means for expanding and contracting the form 21 comprises a cam member 25 shown best in Figures 4 and 8, which is carried by a rock shaft 26 journaled vertically in a bearing portion 27 at the forward end of the bracket arm 10. This cam 25 rides in oppositely disposed recesses 28 and 29 in the arms 15 and 16, and is of the general shape shown in Figure 4, having a pair of oppositely disposed arcuate faces 30 and 31 eccentrically disposed with reference to the axis of the shaft 26, so that by rocking the shaft 26 the cam 25 is moved from the angular position shown in full lines in Figure 4 into the dash line position, the portions 19 and 20 are wedged apart. These portions are normally pressed toward each other as far as permitted by the cam 25, this being accomplished, as shown in Figures 5 and 7, by a spring 35 which engages pins 36 secured to the arms 15 and 16. The extent of separation of these arms 15 and 16 may be limited by adjustable stop screws 40 threaded through web members 41 depending from the lower portion of the bracket arm 10 and having check nuts 42 thereon by which they may be fixed in adjusted position.

Means may be provided for predetermining the amount of expansion of the form 21 so that it may be suitable for any particular size and style of shoe which is to be treated. To this end, as shown best in Figures 2, 3 and 8, there is journaled on the upper end of the shaft 26, a stop disk 45. This stop disk is provided with an

arcuate slot 46 therethrough and also with a stop bolt 47. As shown best in Figure 8, the stop bolt 47 has a manipulating nut 48 threaded on its upper end, and it has a head portion 49 which rides in a socket 50 in a boss 51 projecting upwardly from the disk 45. This stop bolt 47 projects below the head 49, as at 52, to form a latch element, which may be engaged in any one of a plurality of holes 53 arranged in arcuate formation about the axis of the shaft 26 in a flange 54 at the upper end of the bearing 27. The bolt 47 is formally held downwardly with its head 49 in engagement with the upper face of the flange 54, and its portion 52 in engagement in any selected of the holes 53, by a coil spring 55. This spring is housed within the socket portion 50 and bears at its upper end against the base of the socket, and at its lower end against the upper face of the head 49. By grasping the nut 48, the bolt 47 may be retracted against tension of the spring 55, whereupon the disk 45 may be turned about the shaft 26 and the portion 52 engaged in any other of the holes 53. Thus the disk 45 may be fixed in any selected of a plurality of angular positions about the shaft 26, determining the angular position of the slot 46. The limit of expansion of the form is thus fixed at any selected of a plurality of definite extents, differing from each other by definite increments, each selected adjustment corresponding to a definite shoe width. The upper end of the shaft 26 has suitably secured thereto, as by the set screw 60, a collar 61 provided with an outwardly extending arm 62 which is slotted to receive in the slot the end of a link 63, which is pivotally connected in this slot as by means of a bolt 64. This bolt 64 has its lower end riding within the slot 46, the forward end of this slot defining a limit of motion forwardly of the arm 62, which likewise defines a limit of expanding movement of the form. This slot is preferably of a length so that its rear end does not act as a stop, the inner limit of collapsing of the form 21 being determined by the contour of the cam 25, although if desired, and particularly where the form is expanded to its larger dimensions, the back end of the slot may determine the extent of contraction of the form. This amount of collapsing motion, however, should be sufficient so that engagement of the shoe over the form is facilitated prior to the expansion of the form to substantially fill the shoe opening laterally. It will be noted that the curved contours 30 and 31 of the cam are so gradual as to make the form self-locking in so far as pressure exerted on the outside of the form to contract it is concerned. Means for actuating the bar 63 to cause the expansion or contraction of the form in time with the other actions of the machine will be described later.

60 For pressing the shoe upper against the form in order to produce the desired smoothing of the shoe upper and lining, a pair of outer pressing members 70 are provided. Each of these outer pressing members is shown as provided with a pressing pad 71 of leather, or other suitable material, which is designed to contact directly with the outer face of the shoe upper placed over the form, and a suitable backing member 72 for this facing, the parts being so formed that the contour of the pressing face of each member is substantially complementary to the confronting face of the form. In order that the pressing members may conform to the longitudinal contour of the inner form, they are shown as freely pivoted, as 75 on the pivot pins 73, which are in general trans-

verse to the longitudinal axis of a shoe placed on the form. This arrangement will take care of the varying spacing and angular relation between the outer faces of the form as the relatively movable parts of the form swing about their pivotal connection with the bracket 2.

Each pivot 73 is carried by a block 75, which is carried on a pivot 76, substantially parallel to the longitudinal axis of the shoe, by the upper end of an arm 77. Each of these arms is pivoted 10 at 78 intermediate its length to the bracket 2 so that as these arms 77 are swung about their pivotal connections, the outer presser members are moved from and toward the sides of the form about axes substantially parallel to the length of the shoe on the form. These arms are actuated by suitable means, and, as herein shown, they are extended below the pivot 78, and their lower ends are forked as at 80. In these forks are journaled the pivot pins 81 which are perforated for the 20 slidable reception of a pair of toggle links 82. The inner ends of the toggle links 82 are provided with forked portions 83, between the forks of which are pivoted at 84 opposite end portions of a connecting link 85 secured to a bar 86 slidably 25 guided at its upper end through a bearing 87 in the bracket 2. This bar moves substantially perpendicular to the lower end of the arms 77 within their limits of motion. To the lower ends of this rod 86 are pivotally connected, as on the pin 88, a pair of links 89, which, in turn, are connected through a pivot 90 with a hand lever 91. This hand lever is fulcrumed as at 92 to the lower end of the bracket 2 so that as its forward handle portion 93 (see Figure 5) is depressed, the links 30 89 are drawn downwardly, carrying with them the inner ends of the toggle links 83 to "make" the toggle. This action of the links is transmitted to the lower ends of the arms 77 through a pair of springs 93 surrounding the links 82, and 40 reacting at one end of each on a shoulder 94, and at the other end on a washer 95, bearing against the pivot 81. The outer end of each of the toggle links is provided with a collar 96 which is held up against the corresponding pivot 81 by 45 the check nuts 97 threaded on the outer ends of the toggle levers. Adjustment of this nut 97 adjusts the outer limits of the motion of the side presser members. Thus depression of the handle 93 brings the side presser members inwardly 50 against the outside of the shoe upper placed on the form, with yielding pressure.

It is desirable that the outer presser members effect a wiping action on the upper as they come into pressing relation therewith, and this may be 55 accomplished to an adjustable extent by permitting the presser members to engage with the upper first adjacent to its upper edge, and then progressively away therefrom in a manner to produce rocking of the presser members upwardly 60 about the pivot 76. The extent of this rocking may be adjusted for each of the outer presser members by the limit screws 100 and 101. A spring 102 surrounding each stop screw 101 and bearing between a lug 103 on the block 75 and a 65 lug 104 on the corresponding arm 77, acts to press the outer presser forms into such angular position that the contact with the shoe is made first at the desired location for the wiping action to be effected as the outer presser members are 70 moved to final pressing position.

Beside actuating the side presser members, the handle 93 may also be arranged to expand the form from its contracted position, which will permit the ready placing of the shoe thereon. 75

into an expanded position proper for the particular size of shoe being treated so that by the time the presser members are engaged therewith the form is properly distended to present the shoe upper in proper relation between the form and the presser members. As shown in Figures 1 and 5, the lever 91 is extended rearwardly of the pivot 92 as at 110, this portion of the lever being forked, and between the forks is extended a pivot 111. This pivot is perforated for the slidable reception of a rod 112. This rod 112 is provided with a pair of coil springs 113 and 114 surrounding it and reacting between spaced fixed collars 115 and 116 secured thereto, and collars 117 and 118 slidable on the rod 112 and pressed by the springs 113 and 114 into contact with the pivot 111. Thus as the lever 91 is rocked, the pivot 111 is moved up or down against the action of one or the other of the springs 113 and 114, thus to impart a yielding thrust in one or the other direction of the rod 112. At its upper end the rod 112 is pivoted at 120 to one arm of a bell crank lever 121 fulcrumed at 122 on the bracket 1, the opposite end of this lever having pivotal connection at 123 with the bar 63, the movement of which actuates the spreader cam 25 for the form. Thus, when the handle 93 is pressed downwardly to bring the outer presser members toward the form, the rod 112 is moved upwardly, and the bar 63 moved forwardly, so as to expand the form as far as is permitted by the slot 46 of the disk 45. Further motion of the handle 93 after the motion of the bar 63 is stopped by contact of the bolt 64 against the end of the slot 46, is expanded in compressing the spring 113.

In Figure 9 is shown a modified construction in which the expansion of the form is accomplished by hand and without relation to the actuation of the side presser members. Referring to this figure, it will be noted that the shaft 26a, which carries the expanding cam in place of the shaft 26 shown in Figure 8, has keyed thereto a collar 130 which rests on the top of the bearing 54. This collar 130 has an integral handle portion 131 to which is pivoted at 132 a latch lever 133. The inner end of this latch lever engages a latch pin 134 normally spring pressed downwardly by the spring 135 so that its lower end 136 beneath a head 137 thereon may engage in any selected of a plurality of holes 138 arranged in circular series in the top face of the bearing 27 corresponding to the holes 53 shown in Figures 2 and 8. By pressing down on the outer end of the lever 133, the latch pin 134 may be retracted and the collar 130 and the cam shaft 26a be turned to any other desired position of adjustment in which the latch pin 134 may engage in one of the other holes 136.

From the foregoing description of certain embodiments of this invention, it should be evident to those skilled in the art that various changes and modifications may be made without departing from the spirit or scope of this invention as defined by the appended claims.

I claim:

1. In combination, an expandible and contractible form over which a shoe may be placed, rocking means for expanding said form, a stop angularly adjustable about the rocking axis of said rocking means, and means for actuating said rocking means from between contracted position and the expanded position determined by the setting of said stop.

2. In combination, an expandible and contractible form over which a shoe may be placed, means

for adjustably fixing the limit of expansion of said form to any selected of a plurality of definite extents differing from each other by definite increments, means movable from and toward said form to press the upper of a shoe on said form against the surface of said form, and means actuable to move said pressing means to and from said form and to expand and contract said form to and from the limit set. 5

3. In combination, a support, a form over which a shoe may be placed, said form comprising side sections pivoted together and to said support to expand and contract said form, a rocking cam between said sections shaped to swing said sections apart or to permit them to approach 15 each other as said cam is rocked, yielding means holding said sections swung toward each other as far as permitted by said cam, a pair of side presser members, one on each side of said form, pivoted arms carrying said side presser members to swing 20 said members from and toward said form as said arms are swung, a lever, operative connections between said lever and arms to cause rocking of said lever to swing said arms, means actuated by the rocking of said lever for rocking said cam, 25 and means adjustably limiting the rocking of said cam in form-expanding direction, said rocking means including yielding mechanism permitting said lever to be rocked through its full amplitude regardless of the setting of said limiting 30 means.

4. A machine comprising a form over which a shoe may be placed, a pair of presser members engageable with opposite sides of a shoe on said form, a pair of pivoted arms supporting said 35 members, a pair of toggle links to which said arms are pivotally and slidably connected, spring means for pressing said arms yieldingly in one direction along said links, stops on said links for limiting the action of said springs, and means 40 actuatable to make and break said toggle.

5. A machine comprising a form over which a shoe may be placed, a member for pressing a portion of the shoe upper against said form, a pivoted arm carrying said member for motion 45 about the pivot toward and from said form, a movable member mounted for motion transverse to the pivot of said arm and substantially transverse to the direction of motion of said arm in swinging said movable member, a link pivoted to 50 said movable member, and pivoted for sliding motion relative to said arm, and a spring connection between said link and arm yieldable on motion of said movable member in a direction to close said presser member toward said form. 55

6. A machine comprising a form over which a shoe may be placed, a pair of presser members engageable on opposite sides of a shoe on said form, pivoted arms carrying said members for swinging motion toward and from said arm, a 60 member movable between said arms, a pair of toggle links pivoted to said member, pivot elements journaled in said arms and perforated for the slidable reception of said toggle links, springs surrounding said links and acting on said pivot 65 elements, and means actuatable to move said movable member to make and break the toggle and swing said arms under the yielding pressure of said springs.

7. A machine comprising a form over which a 70 shoe may be placed, a pair of presser members engageable with opposite sides of a shoe on said form, pivoted arms carrying said members for swinging motion toward and from said form, a member movable between said arms, a pair of 75

toggle links each having a shoulder and pivoted to said member, pivot elements journaled in said arms and perforated for the slidable reception of said toggle links, springs surrounding said links and reacting between said shoulders and said pivot elements, and means actuatable to move said

movable member to make and break the toggle and swing said arms under the yielding pressure of said springs in a direction to move said presser members toward said form.

JOHN F. SMITH. 5

CERTIFICATE OF CORRECTION.

Patent No. 2,167,410.

July 25, 1939.

JOHN F. SMITH.

It is hereby certified that error appears in the printed specification of the above numbered patent requiring correction as follows: Page 3, second column, line 27, claim 3, for "is" read in; and that the said Letters Patent should be read with this correction therein that the same may conform to the record of the case in the Patent Office.

Signed and sealed this 29th day of August, A. D. 1939.
